UNITED STATES PATENT OFFICE.

HENRY E. HYATT, OF SINGER, LOUISIANA.

WATCH DETAIL.

1,332,295.

Specification of Letters Patent.

Patented Mar. 2, 1920.

Application filed January 9, 1918. Serial No. 211,060.

To all whom it may concern:

Be it known that I, HENRY E. HYATT, a citizen of the United States, residing at Singer, in the parish of Beauregard and 5 State of Louisiana, have invented a new and useful Watch Detail, of which the following is a specification.

It is the object of this invention to provide a novel means for preventing dust from 10 entering the end of a watch pendant, and to improve the construction of the nut against which the stem-controlling spring abuts.

It is within the province of the disclosure 15 to improve generally and to enhance the utility of devices of that type to which the present invention appertains.

With the foregoing and other objects in view which will appear as the description 20 proceeds, the invention resides in the combination and arrangement of parts and in the details of construction hereinafter described and claimed, it being understood that changes in the precise embodiment of the invention herein disclosed can be made 25 within the scope of what is claimed without departing from the spirit of the invention.

In the drawings:

Figure 1 shows in section, a portion of a 30 watch embodying the improvements herein- after claimed;

Fig. 2 is a perspective view showing the nut which forms an abutment for one end of the stem-spring;

Fig. 3 is a bottom plan of the nut.

The numeral 1 marks a watch case carrying a pendant 2 in which a ring 3 is supported in the usual manner. A crown 4 is provided and is supplied with a recess 5 in which the outer end of the pendant 2 is slidably and rotatably received. A stem 6 is disposed within the pendant 2 and is threaded at its outer end, as shown at 7, the stem being connected in this way with the crown 4. A washer 8, made of felt or other yieldable material, is seated in the recess 5 and surrounds the stem 6. The washer 8 abuts against the end face of the pendant 2 and turns with the stem 6 and the crown 4, the washer fitting closely in the recess 5 and being held by the threads 7 on the stem. If desired, the washer 8 may be held to the crown by a touch of cement. The washer 8 prevents the entrance of dust into the watch case.

5 A nut 10 is threaded at 11 into the pendant 2, and aids in supporting the washer 8.

The nut 10 has a central recess 12 in its inner end. Longitudinal openings 14 and a central opening 9 are formed in the nut 10. Pins 15 are frictionally held in the openings 60 14. The stem 6 is mounted to slide and to rotate in the opening 9. Adjacent its inner end the stem 6 is provided with a head 16. A compression spring 17 in the pendant 2 surrounds a portion of the stem 6 and bears 65 at its ends against the nut 10 and against the head 16, one end of the spring being received in the recess 12. The spring 17 serves to hold the washer 8 seated on the end of the pendant 2 and on the nut 10. 70

In the ordinary construction, the stem 6 rotates within such a member as the washer 8. As a consequence, the stem soon forms an enlarged hole in the washer through which dust enters. It is to be observed that 75 in this device the washer 8 is held securely on the stem 6 and in abutment with the crown 4, so as to rotate with these elements. The stem 6, therefore, never wears an enlarged hole in the central portion of the 80 washer 8.

The openings 14 in the nut 10 are adapted to receive the fingers of a spanner wrench (not shown) whereby the nut may be rotated. The fingers of the spanner wrench 85 are pressed against the pins 15 which, being frictionally held in place, slide inwardly and permit the fingers to enter the openings 14. In this way, the nut 10 may be threaded out of the pendant 2. In a similar way, the 90 nut may be threaded into the pendant, the pins 15 subsequently being inserted into the openings 14, as shown in the drawings. Since the openings 14 are closed by the pins 15, dust cannot find its way into the watch 95 through the openings.

Having thus described the invention, what is claimed is:

A watch comprising a pendant; a nut threaded into the pendant and having 100 wrench-receiving openings, the outer end of the nut being flush with the outer end of the pendant; pins frictionally held in the openings and having their outer ends flush with the outer surface of the nut; a crown 105 having a recess receiving the outer end of the pendant, the crown being rotatable on the pendant; a stem journaled in the nut and carried by the crown, the stem being provided adjacent to its inner end with a 110 head; a yieldable washer in the recess and fixed for rotation with the crown and the

stem in contact with the outer end of the pendant, the outer end of the nut and the outer ends of the pins; and a spring interposed between the head and the nut and constituting means for maintaining the washer seated on the pendant, on the nut and on the outer ends of the pins.

In testimony that I claim the foregoing as my own, I have hereto affixed my signature in the presence of two witnesses.

HENRY E. HYATT.
